UNITED STATES PATENT OFFICE.

NEWTON A. MEYER, OF GRANBY, QUEBEC, CANADA.

PROCESS OF MANUFACTURING ROUGH TEXTURE BRICK FROM SOFT MUD AND APPARATUS THEREFOR.

Application filed November 17, 1925. Serial No. 69,641.

To all whom it may concern:

Be it known that I, NEWTON A. MEYER, subject of the King of Great Britain, residing at Granby, Province of Quebec, Canada, have invented certain new and useful Improvements in Processes of Manufacturing Rough Texture Brick from Soft Mud and Apparatus Therefor; and I do hereby declare that the following is a full, clear, and exact description of the invention, such as will enable others skilled in the art to which it appertains to make and use the same.

The present invention pertains to a novel process of manufacturing rough texture brick from soft mud and apparatus for carrying out the process.

The principal object of the invention is to make possible the manufacture of rough texture brick from the cheap soft mud which is now used only for common brick. Secondly, this invention enables the manufacturer of soft mud brick to make wire cut, rugged and raked face brick with the ordinary apparatus supplemented by only a few additional parts with a slight addition to the manufacturing costs.

The process consists essentially in casting in a mould a soft mud slab having the aggregate area of a number of finished bricks. The slab, while plastic, is cut by a frame into a number of sections of brick size. The cutting frame consists of a rectangular member divided by means of wires or cutting bars into a number of brick-size sections. The passage of the cutting elements into the slab for separating the same into a number of bricks imparts to the face of the bricks a rough texture surface according to the nature of the cutting element employed.

The apparatus for carrying out the process includes, first, a mould for casting the slab. A cutting base is also provided on which the slab is deposited from the mould. Finally, there is the cutting frame which is passed into the slab while the latter rests on the cutting base. The various parts are provided with appliances for facilitating the entrance of the cutting elements into the slab and for guiding the movement of these elements through the slab. The soft mud is prepared for moulding and the separate bricks are finished in the usual manner. The additional parts required for

carrying out this process are of simple construction and add very little to the cost of the present soft mud manufacturing equipment.

The invention is fully disclosed in the following description and in the accompanying drawings in which;

Figure 1 is a perspective view showing the removal of the mould after the slab has been deposited on the cutting base;

Figure 2 is a perspective view showing the operation of inserting the cutting frame into the slab;

Figure 3 is a perspective view showing the removal of the cutting base after it and the cutting frame have been inverted on the pallet;

Figure 4 is a perspective view showing the removal of the cutting frame from the slab;

Figure 5 is a perspective view showing the interior of the mould;

Figure 6 is a perspective view showing the working surface of the cutting base;

Figure 7 is a perspective view of a modified form of cutting frame;

Figure 8 is a longitudinal section of the cutting base;

Figure 9 is an end view, partly in section, of the cutting base; and

Figure 10 is a fragmentary longitudinal section of the mould.

Reference to these views will now be made by use of like characters which are employed to designate corresponding parts throughout.

A slab of soft mud having the aggregate area of a given number of bricks, preferably six, is formed in a mould such as that shown in Figure 5. The bottom 1 of the mould is surrounded by side walls 2 and end walls 3 forming the cavity for casting. The bottom of the mould carries a number of plates 4 corresponding in number to the bricks that will be made from the slab, and these plates are adapted to impress a trademark or the like on each such brick.

A number of these moulds are filled in a soft mud brick machine in the usual manner. Prior to emptying the moulds, a base 5 for each mould is laid on a pallet 6 which is on the usual pallet holder of the turn-table. The base consists of a backing board 7 to which are secured a plurality of board sections 8 equal in number and similar in ar-

- rangement to the bricks that will be formed from the slab. Spaces 9 are retained between the sections 8, and metallic plates 10 are secured to the sections with their edges turned down into the spaces as indicated by the numeral 11 in Figure 8. The longitudinal space 9 is enlarged as at 12 at its ends to permit entrance of the hands of the operator in order to grip the handle straps 13 bridged across the enlargement 12 and move the base as required. Guide fingers 14 are secured to the edges of the base for the purpose pointed out below.
- The mould is next carried from the soft mud brick machine, emptied on the base, and lifted from the slab deposited on the base as illustrated in Figure 1.
- The next operation is to cut the slab into a number of separate bricks by means of a cutting frame. This device consists of rectangular members 16, as shown in Figure 2, having cutting rakes 17 stretched between the sides and ends thereof, dividing the interior of the frame into a number of brick-size sections. The sides of the members 16 are provided with guide notches 18 which receive the fingers 14 and thus determine the path of travel which the frame takes while being pressed into the slab. The cutting frame carries a number of coil springs 19 between which are provided spring clips 20. When the frame reaches its lowermost position, the coil springs 19 are compressed and the spring clips 20 lock against the handle straps 13. This assembly, comprising the cutting base, slab and cutting frame, is now inverted so that the cutting base lies on the pallet 6 as shown in Figure 3. It is now necessary to remove the cutting base, and the clips 20 are pressed inwardly to remove it from the cutting frame. The base is now lifted as shown in Figure 3, leaving only the cutting frame and the slab on the pallet holder. Finally, the cutting frame is withdrawn as illustrated in Figure 4, leaving the separate bricks on the pallet holder. The bricks are then removed for drying and finishing in the usual manner.
- The passage of the rake bars 17 of the cutting frame through the slab imparts a raked face to the brick, resembling the appearance of a brick made by the stiff mud process. Instead of the rake bars, the cutting frame may be provided with similarly disposed wires 21 as shown in Figure 7. This frame is used in the manner already described and forms a wire cut face also resembling that produced on a stiff mud brick. It is to be understood that the cutting elements of the cutting frame may have various forms for the purpose of imparting different kinds of faces to the brick. The essential feature of the invention re-

mains the same, namely, that a number of 65 rough texture faced bricks are formed by cutting a soft mud slab.

While a specific embodiment of the invention has been illustrated and described, it is to be understood that various alterations 70 in the details of construction may be made without departing from the spirit of the invention as indicated by the appended claims.

Having thus fully described the invention, what I claim as new and desire to protect by Letters Patent is:

1. A process of manufacturing rough texture brick consisting in casting a slab of soft mud brick material in an undivided 80 mould, depositing said slab on a base, inserting in said slab, while plastic, a cutting frame which divides the slab into a plurality of bricks having a rough texture surface, inverting the base, slab and frame collectively, and successively withdrawing said base and frame from the slab.

2. An apparatus for manufacturing rough texture brick from soft mud comprising an undivided mould adapted to form a slab 90 of brick material having the aggregate area of a plurality of bricks, and a cutting frame having substantially the internal dimensions of the mould and divided into a plurality of brick-size sections. 95

3. An apparatus for manufacturing rough texture brick from soft mud comprising an undivided mould adapted to form a slab of brick material having the aggregate area of a plurality of bricks, and a cutting frame 100 having substantially the internal dimensions of the mould, and a plurality of cutting elements dividing the frame into brick-size sections.

4. An apparatus for manufacturing rough 105 texture brick from soft mud comprising an undivided mould adapted to form a slab of brick material having the aggregate area of a plurality of bricks, a cutting base adapted to receive the contents of said mould, 110 and a cutting frame having substantially the internal dimensions of the mould and divided into a plurality of brick-size sections.

5. An apparatus for manufacturing rough 115 texture brick from soft mud comprising an undivided mould adapted to form a slab of brick material having the aggregate area of a plurality of bricks, a cutting base adapted to receive the contents of said mould, 120 and a cutting frame having substantially the internal dimensions of the mould, and a plurality of cutting elements dividing the frame into brick-size sections.

In witness whereof I have hereunto set 125 my hand.

NEWTON A. MEYER.
